GEORGE M. HILL AND ONE-FOURTH TO EARL M. HILL, BOTH OF GRAND RAPIDS,
WISCONSIN

CARRIAGE AND MOVABLE TRACK THEREFOR.

1,144,793

Specification of Letters Patent. Patented June 29, 1915.

Application filed October 9, 1911. Serial No. 653,515.

To all whom it may concern:

Be it known that I, CHARLES W. Rood, a citizen of the United States, residing at Grand Rapids, county of Wood, State of Wisconsin, have invented a certain new and useful Improvement in Carriages and Movable Tracks Therefor, and declare the following to be a full, clear, and exact description of the same, such as will enable others skilled in the art to which it pertains to make and use the same, reference being had to the accompanying drawings, which form a part of this specification.

My invention has for its object to produce a simple and novel arrangement for effectively supporting heavy apparatus, such as excavating machinery, and for moving it easily and conveniently as occasion demands during its working operations or for transporting it from one place to another.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a side elevation of an excavating machine arranged in accordance with a preferred form of my invention; and Fig. 2 is a plan view of the machine, on a somewhat larger scale, all of the structure and parts above the main floor frame being omitted for the purpose of exposing the novel features of my invention which would otherwise be concealed.

Referring to the drawings, 1 represents the carriage of an excavating machine having a crane 2 supported at its lower end upon a turn-table 3 which is adapted to be rotated about a vertical axis. Hanging beneath the crane is a boom 4 on the outer end of which is supported an excavating bucket 5. All of these parts may take any usual or preferred forms since they of themselves form no part of the present invention.

Secured to the underside of the carriage at the sides thereof, and extending longitudinally thereof are shoes 6 and 7, these being preferably made of heavy wooden beams, faced if desired, with metal as indicated at 8. The shoes are adapted to rest upon rollers mounted upon and forming

part of suitable tracks which rest upon the ground beneath the carriage. The two tracks are indicated as a whole by the reference characters 9 and 10 and they are preferably somewhat longer than the carriage so that the carriage may be moved along the tracks for some distance without losing its support at one end. The tracks are preferably so arranged that they have a large bearing surface on the ground which supports them, thereby permitting the weight of the carriage to be distributed over a large supporting surface and preventing the tracks from sinking deeply into the ground if it should happen to be soft and wet. In the arrangement shown each track 70 comprises a base member 11 made up of one or more long planks laid side by side and connected together by suitable cross pieces or cleats 12 fastened thereto on the upper side. Lying above the base member of each track and extending longitudinally thereof are two long heavy beams 13 and 14. Supported upon the beams and lying between the same are a series of transverse rollers 15 mounted in suitable bearings 16 arranged 80 along the tops of the beams.

The tracks are placed under the carriage so that each of the shoes, 6 and 7, rests upon the rollers of one of the tracks. Consequently the carriage may be moved along 85 the tracks with very little effort.

I contemplate moving one of the tracks at a time whenever it is desired to shift the tracks bodily along the ground beneath the carriage. I take the weight off the track 90 which is to be shifted by filling the excavating bucket and swinging the crane around to the opposite side of the carriage from that beneath which the track to be moved is placed. The crane thus forms a lever on 95 the outer end of which the pull of the weighted bucket is exerted and the carriage becomes balanced upon one of the tracks, leaving the other track practically free. Suitable cable connections are provided between the carriage and the track so as to produce a relative movement between the carriage and the free track. If the free track has become partially embedded in the ground there may be more resistance to its 105 movement over the ground than to a movement of the carriage itself and therefore, in order to prevent the carriage from mov-

ing relatively to the ground when it is desired to shift one of the tracks, I provide the carriage with suitable anchors which prevent it from moving when a pull is exerted upon one of the tracks. The anchors are indicated as a whole at 17 and 18, there being one near the rear end of the carriage on each side thereof. In the preferred form, each anchor comprises a leg or post 19 pivotally connected at its upper end to the framework of the carriage as at 20 and provided at its lower end with a comparatively long shoe 21. Each of the posts 19 is made longer than the vertical distance from its pivotal axis to the under surface of the tracks, so that normally the posts lie at an angle to the vertical, their disposition being such that their lower ends extend forward of the pivotal axis. The relative movements between the carriage and the tracks are effected by power devices which act at one end upon the tracks and at the other end upon the anchors, the force upon the anchors being applied in the direction which tends to bring them into more nearly vertical positions. Thus the carriage is locked in place and furthermore, if the weight of the rear end thereof has not already been removed from the track which is to be moved, the anchor exerts a lifting effort and cooperates with the weighted crane to release the entire track from the weight of the carriage.

Referring again to the drawings, 22 and 23 are two drums suitably mounted upon the carriage and driven by any suitable means, not shown. Secured at one end upon the drum 22 is a cable 24 which passes over a sheave 25 mounted upon the rear end of the carriage, then around a sheave 26 carried by the track 9, then around a second sheave 27 on the rear end of the framework of the carriage and to the anchor 17 to which the free end of the cable is connected as indicated at 28. It will be seen that when the drum 22 is revolved so as to wind up the cable 24, a pull is exerted upon the anchor 17 which tends to pull its lower end toward the rear. As soon as the anchor takes a firm hold the track 9 begins to move back, this movement continuing until the track projects beyond the rear end of the carriage as far as the actuating cable will permit. Similarly, a cable 29 connected at one end to the drum 23 passes over pulleys 30, 31 and 32, corresponding respectively with pulleys 25, 26 and 27, and is secured at its other end to the anchor 18 as indicated at 33. Consequently by rotating the drum 23 the track 10, on which the sheave or pulley 31 is mounted, is moved toward the rear relative to the carriage; it being understood that when the track 9 is to be moved, the loaded crane is swung to the side on which the track 10 lies, while when the track 10 is to be moved the loaded crane is swung to the op-

posite side. It will thus be seen that the tracks may be moved without suspending the excavating operations, the excavating bucket being filled in the regular way and being simply swung to one side or the other to be dumped when a movement of the tracks is to be effected.

The carriage may be moved backward over the tracks in any suitable way, preferably by means of a power device. In the arrangement shown there is a drum 35 which may be actuated in any suitable way, not shown, to which one end of a cable 36 is fastened. The drum 35 lies at the rear end of the carriage and the cable extends toward the front where it passes around a sheave or pulley 37 and then back toward the rear of the carriage where it is divided into two branches 38 and 39 respectively, each of which is secured to one of the tracks near the rear ends thereof. When the drum 35 is rotated the cable is wound up thereon and the carriage is drawn toward the rear, the anchors dragging idly over the ground and offering no obstruction to the rolling of the carriage over the tracks.

While I have illustrated and described only a single preferred form of my invention, I do not desire to be limited to the particular structural details thus illustrated and described; but intend to cover all forms and arrangements which fall within the terms employed in the definitions of my invention constituting the appended claims.

I claim:

1. In combination, tracks adapted to rest loosely on the ground, a carriage mounted on the tracks so as to be movable lengthwise of the tracks and be held against movement in the transverse direction, means for balancing the carriage on one of the tracks so as at least partially to remove the weight on the other track, and means for producing relative movements between the latter track and the carriage in the direction of the length of the tracks.

2. In combination, tracks adapted to rest loosely on the ground, a carriage mounted on the tracks so as to be movable lengthwise thereof and be held against movement in the transverse direction, a crane mounted on one end of the carriage so as to be movable about a vertical axis, the crane being of sufficient size to permit it to overhang the aforesaid end of the carriage and when swung to one side or the other to project outwardly from the side of the carriage, the crane having sufficient weight to cause the track on one side to be partially relieved of the weight of the carriage when the crane is swung to the opposite side of the carriage, and means for producing relative movements between the latter track and the carriage in the direction of the length of the tracks.

3. In combination, a carriage, tracks un-

der said carriage at opposite sides thereof, means for balancing the carriage on one of the tracks so as at least partially to remove the weight on the other track, a swinging anchor pivotally mounted on the carriage on the side of the latter track and lying at an angle to the perpendicular, and power devices between the latter track and the carriage and the anchor tending to swing the anchor into a perpendicular and to produce a relative movement between the latter track and the carriage.

4. In combination, a carriage, a track under each side of said carriage, wheels for supporting the carriage on the tracks, means for balancing the carriage so as to throw substantially the whole weight on either of said tracks and at least partially remove the weight on the other track, anchors at the sides of the carriage, and power devices each constructed and arranged to draw one of the anchors into operative relation to the ground so as to hold the carriage against movement

in one direction and at the same time move the corresponding track.

5. In combination, a carriage, a track under each side of said carriage, wheels for supporting the carriage on the tracks, means for balancing the carriage so as to throw substantially the whole weight on either of said tracks and at least partially remove the weight on the other track, anchors at the sides of the carriage, and power devices each constructed and arranged to draw one of the anchors into operative relation to the ground so as to hold the carriage against movement in one direction and at the same time move the corresponding track, and means for moving the carriage on the tracks when both anchors are in their inoperative position.

In testimony whereof, I sign this specification in the presence of two witnesses.

CHARLES W. ROOD.
